DROP DOOR FOR RAILWAY CARS

Filed Oct. 24, 1929

Inventor:
Arthur E. Small
Clinton Essissor
Attorney

UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

DROP DOOR FOR RAILWAY CARS

Application filed October 24, 1929. Serial No. 402,013.

My invention relates to the construction of railway cars of the dumping or drop bottom type, such as hopper cars, hopper gondola cars, drop bottom or general service gondola cars or the like, having a door forming a part of the load retaining means, which door is provided with hinges adjacent one of its edges and is capable of being dropped or swung open to discharge the load. Any means of raising the door to the closed position and any means for locking and releasing the door may be employed with my door.

The door may also be used as an end door or end gate of a "mill type gondola" wherein the sides of the car are rigid but the end walls are hinged to the car at their lower margins so that they can be dropped or lowered to a horizontal position to permit the car to be used for transporting articles longer than a single car, such as fabricated girders and beams, poles, pipes, etc.

An object of the invention is to provide a very strong cast metallic door by distributing the metal according to the service stresses imposed upon the component parts which I accomplish by providing the main part of the door with a flange, portions of which are adjacent the side and end margins, respectively, of the door which are connected by substantially oblique portions spaced apart from the margins, and if desirable, the corners of the door may be reinforced by brackets projecting from the flange. I preferably reinforce the main part of the door by a spider comprising various length ribs radiating from a common center adjacent the center of the door.

I prefer to make the door of cast metal because a better distribution of the metal for strength requirements can be obtained without the use of separate fixtures, and furthermore, cast metal has greater resistance to corrosion than rolled steel.

Another object of the invention is to provide a door of cast metal formed and shaped so that it will not be deformed by warping when cooling, and furthermore, will eliminate shrinkage cracks and the internal stresses.

In the drawings:

Figs. 1 to 4 inclusive show a typical door according to my invention.

Figs. 5 and 6 show a modified form.

The door comprises a main portion 2, which is preferably flat, and a flange having portions 3 adjacent the respective margins of the door and other portions 4 connecting them which are spaced apart from such margins. The portions 3 of the flange adjacent the margins are preferably parallel thereto for a short distance adjacent the middle of the respective margins and the connecting portions 4 are positioned at substantially a forty-five degree angle therefrom so that the flange forms approximately an octagon, as shown in Fig. 1. This flange (6), however, may be a circle, as shown in Fig. 5.

The main part 2 of the door is further reinforced by a spider comprising ribs 10 radiating from substantially the center of the door which merge into the main part of the door adjacent the flange (3 or 4). This construction is shown in Fig. 1. In the modified form shown in Figs. 5 and 6 I provide a central substantially circular flange 13 from which the ribs 10 and 11 radiate. The number, depth and length of the ribs depend, of course, upon the size of the door and the load to be sustained thereby.

The hinge lugs 15 are preferably cast integral with the door as well as the lifting brackets 16. These lugs and brackets may be of any convenient form to suit the requirements.

In the design shown in Figs. 1 to 4 inclusive I have shown a bumper 17 for engagement with a stop on the car.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A door forming part of the load retaining means of a railway car comprising a main part, a flange having portions adjacent the respective margins of the door and

other portions connecting the first mentioned portions which are spaced apart from said margins, and ribs radiating from substantially the center of the door which merge into said main part adjacent said flange.

2. A door forming part of the load retaining means of a railway car comprising a main part, a flange having portions adjacent the respective margins of the door and other portions connecting the first mentioned portions which are spaced apart from said margins, ribs radiating from substantially the center of the door, and other shorter ribs radiating from the same center as the first mentioned ribs.

10 3. A door forming part of the load retaining means of a railway car comprising a main part, a flange having portions adjacent the respective margins of the door and other portions connecting the first mentioned portions which are spaced apart from said margins, ribs radiating from substantially the center of the door which merge into said main part adjacent said flange, and other

20 25 shorter ribs radiating from the same center as the first mentioned ribs which merge into the main part.

30 35 4. A door forming part of the load retaining means of a railway car comprising a main part, a flange having portions adjacent the respective margins of the door and other portions connecting the first mentioned portions which are spaced apart from said margins, a central substantially circular flange, and ribs radiating from said circular flange from which merge into said main part adjacent said flange.

40 45 5. A door forming part of the load retaining means of a railway car comprising a substantially rectangular main part reinforced by a circular rib having portions touching the edges of the main part so that the corners thereof extend beyond the rib.

50 55 6. A door forming part of the load retaining means of a railway car comprising a substantially rectangular main part reinforced by a circular rib having portions touching the edges of the main part so that the corners thereof extend beyond the rib, and an inner circular rib concentric with the first mentioned rib.

60 65 7. A door forming part of the load retaining means of a railway car comprising a substantially rectangular main part reinforced by a circular rib having portions touching the edges of the main part so that the corners thereof extend beyond the rib, and varying depth reinforcements crossing said main part and merging thereinto adjacent said rib.

8. A door forming part of the load retaining means of a railway car comprising a substantially rectangular main part reinforced by a circular rib having portions touching the edges of the main part so that the

corners thereof extend beyond the rib, an inner circular rib concentric with the first mentioned rib, and reinforcements springing from the last mentioned circular rib and merging into said main part adjacent the 70 first mentioned rib.
